UNITED STATES PATENT OFFICE.

JOSEPH G. HUYE, OF NEW ORLEANS, LOUISIANA.

DISPLAY STAND.

Application filed August 24, 1925. Serial No. 52,060.

This invention relates to collapsible cardboard or paperboard display stands or supports or display "cones" such as commonly used on the counters or display cases 5 in stores to display goods for sale, for instance, as ladies' hats, and has particularly in view to provide such a collapsible set-up display stand of very light material, which in use will be automatically self-setting-up or expanding or 10 erecting, which may be positively locked in set-up condition, which will be capable of standing rough usage, and which may be folded flat and carried in large numbers in 15 folded condition by traveling salesmen and used to display their goods, primarily ladies' hats, to the trade.

The primary object of the present invention is to provide such a display stand 20 adapted to be carried flat with a number of similar stands and which, upon being relieved of the weight of the stand superposed upon it, will automatically set-up expand or erect itself ready for use, thereby conserving 25 the salesman's time in arranging his display. Other objects are to provide such a display stand with bracing and reinforcing means, whereby a lighter weight material may be used while still retaining an 30 ample degree of rigidity and stability; to provide means for positively locking the stand in set-up or erected or expanded condition so that it cannot be collapsed until 35 said means are released; and to provide a very simple and inexpensive construction 40 wherein the means for automatically actuating the stand, said means preferably being a small rubber band at each end, may be easily replaced as the occasion may arise.

While the invention is above referred to 45 as a stand for displaying merchandise, it quite obviously may be equally well used for, and lends itself well to, displaying advertising matter which might be printed 50 on it, either as a single unit or one of a plurality of units combined in a series, or similar novelty advertising purposes.

In the accompanying drawings, in which 55 but several embodiments are shown for the purpose of illustrating the practice of my invention as by law required, it being well recognized that my invention is capable of embodiment in a great many other additional forms not herein shown or described;

Figure 1 represents a plan view of one of 55 the two duplicate blanks from which the preferred or quadrilateral form of my invention is constructed;

Figure 2, a side elevation of the preferred 60 form of my invention;

Figure 3, a bottom plan view thereof;

Figure 4, a sectional view on the line 65 4-4 of Fig. 3, looking in the direction of the arrows;

Figure 5, a bottom plan view of the preferred 70 form in intermediate condition in the early stage of its being erected or set-up, showing the sides bulged as the two opposite corners are being pulled toward each other;

Figure 6, a side elevation of a modified 75 form or hexagonal form device;

Figure 7, a top plan view of the hexagonal 80 form;

Figure 8, a detail fragmentary view of a 75 modification wherein the springs or rubbers are supplemented by a positive lock;

Figure 9, a fragmentary edge view of the 85 two sliding plates or leaves of the modified form of Fig. 8, on an enlarged scale, to better show the positive lock, the rubber or spring being omitted;

Figure 10, a plan view of a blank for a 90 modified triangular form of device;

Figure 11, a top plan view of the triangular 95 form, set up; and

Figure 12, a bottom plan view of the 100 triangular form, in an intermediate stage.

Referring now in detail to the drawings, in 105 the preferred form, there are two blanks such as illustrated in Figure 1 employed, each blank being scored or creased along lines 1, 2 and 3 for folding, dividing the blanks each into a pasting and reinforcing strip 4, which is coated with adhesive, as illustrated, two 110 panels 5, and a guiding and bracing sliding plate 6, preferably cut out as at 7 to save material, and having two extending arms 8, one at the top portion and one at the bottom portion, as shown, the arms having their 115 upper and lower portions respectively cut away as at 9, and in operation having their sides in sliding engagement with the opposed sides of the corresponding arms of the similar blank or section of which the particular 120 stand is comprised.

The plate 6 will preferably have its portion 125 immediately adjacent the crease or score

3 and extending for its full length coated with adhesive forming a pasting strip 10, and the end portions of the strips 4 and 10 are preferably notched as at 11, each pair 5 of upper and lower notches diverging from each other, each of the notches of the upper pair diverging downwardly away from each other and each of the notches of the lower pair diverging upwardly away from each 10 other, preferably the degree of inclination or divergence of said notches being the same throughout, and said notches 11 being so arranged that the notches 11 in the strip 4 of each of the two blanks forming the device 15 will, in assembling, lie parallel to, and register with, the corresponding upper and lower notches 11 in the strip 10 of the other of said two blanks, the said notches being so arranged that in the finished article the upper 20 per pair of notches 11 will converge downwardly toward each other and the notches of the lower pair will converge upwardly toward each other and toward the upper pair of notches 11.

25 Preferably the strip 4, panels 5, plate 6 and arms 8 of each blank will all be integral as shown, this being a practical and economical construction, but this is not essential so long as such portions are suitably connected. Likewise, the strips 4 and 10 will preferably be coated with adhesive for securing together as indicated, but this is not essential, any other suitable method of securing such parts together, such as stitching, 30 stapling, riveting or the like, being an equivalent for the pasting together, may be employed.

To assemble, the strip 4 and the plate 6 are folded on the creases or scores 1 and 3, 40 respectively, toward each other so as to lie flat against the same side faces of the intervening panels 5. When the two blanks composing the device have been treated in this manner, they are brought into registry with the adhesive coated faces of the strips 4 and 10 of the one blank opposed to, and in registry with, the similar faces of the strips 10 and 4 respectively of the other blank, care being used to see that the slots 11 are in registry in all instances, when the two blanks 45 will be pressed together and the adhesive allowed to set or dry.

Thereafter the corners to which the plates 6 are connected will be forced toward each 55 other until the device is fully spread, set-up, expanded or erected in the form shown in Fig. 3, when a short rubber band 12 will be applied to the upper ends of the plates 6, being inserted in the slots 11 thereof and 60 extending on both sides of said plates 6 as shown, and a similar, but slightly longer, rubber band 13 will be similarly applied to the lower ends of said plates 6, all as clearly shown in Fig. 4, the outer end portions of the 65 arms 8 being cut away at 9, as illustrated and

above mentioned, so as not to interfere with the application of the rubber bands 12 and 13, nor to interfere, by rubbing against them or catching in them, during operation.

Obviously, if one of the rubber bands should break or lose its elasticity it may be quickly removed and as quickly replaced by another; likewise, the degree of tension can be adjusted at will, for instance, by tying a knot in the rubber band.

In operation, to erect, it is simply necessary to release from any superposed article or from restraint, so as to permit the rubber bands 12 and 13 to pull together or telescope the plates 6 into full overlapping normal set-up relation, wherein the opposed corners to which the plates 6 are respectively attached will be pulled toward each other and the other two corners forced apart.

To collapse it is simply necessary to press on the panels 5 in a direction at right angles to the plates 6.

In the modification shown in Figures 6 and 7 the construction and operation are in all respects the same as above described, except that each of the two blanks has three panels 5 instead of but two, resulting in producing a device hexagonal in cross-section instead of the preferred quadrilateral form.

In the modification shown in Figures 10, 11 and 12 the construction and operation are in all respects the same as above described except that it is triangular in form in cross-section and for that reason no adhesive or equivalent rigid connection is employed and but one blank is used, and instead of the strip 4 and the plate 6 cut out at 7, the blank, as shown in Figure 10, has two plates 6^a spaced from each other by two intervening panels 5, the plates 6^a each being provided with the notches 11 arranged and located as above described and are folded over toward each other into overlapping relation against the same side faces of the panels 5 and, as thus arranged, have their opposed side faces in sliding engagement with each other, the panels 5 comprising two of the sides of the stand as set-up and the plates 6^a together constituting the third side, the rubber bands 12 and 13 being respectively to the top and bottom pairs of notches 11 as above mentioned.

In the modification shown in Figures 8 and 9, the construction and operation are the same as described with relation to the forms shown in Figures 1 to 7 except that, in addition to the rubber bands 12 and 13, the upper and lower ends of the plates 6 are centrally notched to provide opposed overlapping tongues 14, the tongues 14 of the one plate 6 preferably extending in the same lateral direction and being opposed to the oppositely presented tongues 14 respectively of the other plate 6, thus constituting upper

and lower pairs of opposed tongues 14 which may be twisted to interlock and so hold the stand in set-up condition against accidental deformation until said tongues 14 are untwisted or unlocked.

Of course, if desired, or if one or both of the rubber bands 12 and 13 should be broken or lost and others not available, these tongues may be interlocked and relied upon 10 to hold the stand in set-up condition without the use of the rubber bands, but this involves the sacrifice of the automatic action, which is preferred where the stands are to be carried about by salesmen and temporarily set 15 up to display their goods and then collapsed and packed away until the salesman reaches another city or new point where he intends to display his goods.

Of course, if in the case of a particular stand, it is to be set up and left permanently 20 in that condition, as, for instance, in use in a show window or on a counter or show case, in all forms described, cord strings, or wires or similar devices may be substituted 25 for the elements 12 and 13, or, for that matter, the plates 6 may be held relatively stationary by a clip or piercing fastener, or, in the modification shown in Figures 8 and 9, the tongues 14 may be twisted to interlocked 30 position and solely relied upon to maintain the parts in correct relation, all other means to this end being dispensed with.

While the term "rubber band" has been 35 used throughout the specification in describing the elements 12 and 13, and while they will usually be, and preferably be, rubber bands such as now in general use for purposes of general utility, it is evident that a 40 spring of any suitable construction or any other suitable resilient or elastic device will suffice, nor is it essential that the rubber bands or equivalent elements lie on both sides of the plates 6, it being sufficient if they be resilient and act to pull or push or

telescope the plates 6 into normal overlap- 45 ping relation.

Having thus described my invention, what I claim as new and desire to secure by Letters Patent is:

1. A collapsible set-up display device 50 comprising a tubular member having a plurality of overlapping plates having their opposed side faces in sliding engagement with each other at all times, and elastic bands fitting about parts of the end portions 55 of said plates to pull them edgewise toward each other into normal full overlapping relation to expand the tubular member to full set-up condition.

2. A collapsible set-up display device 60 comprising a tubular member having two overlapping plates having sliding engagement with each other, resilient means acting on said plates to move them edgewise with relation to each other to expand the tubular 65 member to set-up condition, and means for locking said plates in this latter relation against relative movement, said means comprising tongues extending in opposed relation respectively from said plates and 70 adapted to interlock.

3. A collapsible set-up display device comprising a tubular member having a plurality of overlapping plates having their opposed sides at all times in sliding engagement for 75 movement with relation to each other edgewise in opposite directions, resilient means acting on said plates to move them edgewise with relation to each other to vary the cross-sectional form of said tubular member, and 80 means for locking said plates together in this latter relation against relative reverse movement.

In testimony whereof, I have signed my name to this specification at New Orleans, 85 Louisiana, this 22nd day of August, 1925.

JOSEPH G. HUYE.
